UNITED STATES PATENT OFFICE.

RUSSELL W. MOORE, OF ORANGE, NEW JERSEY.

PERFUMERY-ATOMIZER.

SPECIFICATION forming part of Letters Patent No. 746,866, dated December 15, 1903.

Application filed April 9, 1903. Serial No. 151,767. (No model.)

To all whom it may concern:

Be it known that I, RUSSELL W. MOORE, a citizen of the United States, and a resident of Orange, in the county of Essex and State 5 of New Jersey, have invented certain new and useful Improvements in Perfumery-Atomizers, of which the following is a specification.

My invention relates to atomizers for perfumery; and its novelty consists in the means employed to preserve the liquid perfume and to atomize it.

Perfumes which consist of essential oils or extracts mixed with or dissolved in volatile solvents, such as alcohol, become thick and sticky from the constant evaporation of the solvent around the outlet of the bottle or other receptacle in which they are contained, and this deposit oxidizing by contact with 20 the air causes the odor to deteriorate.

The purpose of my invention is to keep such a perfume out of contact with the air and also to provide means whereby it may be sprayed or atomized on its discharge from 25 the receptacle, so as at once to be dissipated on the air in a light cloud, which disseminates the perfume and reduces the strength of a strong odor.

In carrying out my invention I place the 30 perfume which has been dissolved in or mixed with a volatile solvent in the usual manner in a bottle, in which it is charged with a neutral gas under pressure. By "neutral" I mean a gas which has no odor in itself and 35 one which sets up no deleterious reaction with the body of liquid perfume. In most cases carbonic-acid gas or carbon dioxid is entirely suitable for this purpose, and as it is cheap, readily obtained, and the handling of 40 it under pressure is well understood it is best adapted for such use. Having been introduced into the bottle containing the perfume, it there remains until it is desired to use the latter, when the opening of the discharge-valve permits it to escape either in a 45 solid stream or in fine spray, as may be desired.

The atomizing mixture, by a requirement of the Patent Office, is made the subject of a 50 separate application for Letters Patent.

I have illustrated in the accompanying drawings a suitable form of apparatus in

which to carry my mixture and to discharge it as stated.

In the drawings, Figure 1 is central vertical section of the discharge-nozzles of the apparatus and the upper portion of the bottle. Fig. 2 is a detail showing the valves open and the atomizing operation going on, and Fig. 3 is a detail showing the valve closed.

In the drawings, 1 is the upper portion of a strong receptacle made of glass or other suitable material strong enough to normally resist the internal pressure of the fluids to be contained therein. It is threaded at the 65 top externally at 11 to receive the head 2, which is made of metal and is threaded at 21 to engage with the threads 11 of the bottle and is also provided with a lateral threaded aperture to receive the discharge-spout 30. 70 This discharge-spout is also internally threaded and adapted to receive the block 31, to which are attached the nozzles 4 and 5, 4 being the gas-nozzle and 5 the perfumery-nozzle.

The perfumery-nozzle 4 is bent downward 75 and secured to a cylinder 6, with which it communicates through a passage 51 and which is provided with a transverse diaphragm 52 and with a dependent tube 53, which extends almost but not quite to the bottom of the 80 bottle 1.

A valve 7 is secured to the lower end of a vertical valve-rod 70, passing through suitable apertures in the head 2. At its upper extremity the rod 70 is provided with a push-button 71 and between the top 22 of the head 2 and the lower diaphragm 24 of the cover 23 is encircled by a coiled spring 25 and is provided with an annular lug 26. The valve-rod 70 is also provided with the gas-valve 40, 90 extending laterally therefrom and adapted to press against the terminal opening 41 of the gas-nozzle 4 to close it.

The head 2 is provided with a cover 23, which is provided also with the transverse 95 intermediate diaphragm 24. The purpose of this cover is to protect the valve-rod and button from accidental injury.

The mode of operation of my device is as follows: Supposing the bottle 1 to be filled 100 with the liquid perfume, in part, and in part with carbonic-acid gas under pressure, the pressure of the gas within the tube 53 and underneath the valve 7 will lift the latter

against the seat formed by the under surface of the diaphragm 52 and will close the inlet to the perfume-nozzle 5. Similarly the gas-valve 40 would press against the nozzle 4 to close it. Now if the push-button 71 be pressed downward the valve-rod 70 and the valve 7 are moved downward and the valve 40 is moved away from the inlet 41 of the gas-nozzle 4. The free gas in the upper part of the bottle immediately begins to rush out of the nozzle 4, and as it leaves the tip 42 in a fine stream it creates a vacuum in front of the tip 54 of the nozzle 5 and atomizes the outflowing current of liquid which has been forced upward through the pipe 53, the opening in the diaphragm 52, and the nozzle 5. This spray continues to be delivered so long as the valve is held open and the pressure of the gas is sufficient to maintain it. Now if the pressure upon the button 71 be relieved the pressure within the bottle, if sufficient, presses the valves 7 and 40 upward and closes the ports 41 and 51, leading to the nozzles 4 and 5. If the pressure within the bottle should be insufficient to close these valves by reason of the exhaustion of the gas, the resilience of the coiled spring 25 will be sufficient to press the lug 26 against the diaphragm 24 and keep the valves shut.

Having described my invention, what I claim as new is—

1. An atomizer for perfumery-bottles, adapted to contain perfumery in solution and gas permanently under pressure, comprising a gas-nozzle and a perfumery-nozzle arranged to atomize when in operation, and inlet-valves to each nozzle having a common stem. 35

2. An atomizer for perfumery-bottles, adapted to contain perfumery in solution and gas permanently under pressure, comprising a gas-nozzle and a perfumery-nozzle arranged to atomize when in operation, and inlet-valves to each nozzle having a common stem, in combination with means for keeping each valve normally shut. 40

3. An atomizer for perfumery-bottles, adapted to contain perfumery in solution and gas permanently under pressure, comprising a gas-nozzle and a perfumery-nozzle arranged to atomize when in operation, and inlet-valves to each nozzle having a common stem, in combination with means for keeping the valves shut when the pressure of the gas within the bottle is not sufficient to do so. 45

Witness my hand this 8th day of April, 55 1903, at the city of New York, in the county and State of New York.

RUSSELL W. MOORE.
